(57) **CLAIM**

The ornamental design for a wall panel as shown and described.

DESCRIPTION

1. Wall panel

Figure 1.1 is a front view of the wall panel showing my new design;

Figure 1.2 is an enlarged, partial front view of the wall panel showing a portion of Figure 1.1; and

Figure 1.3 is an enlarged, partial front perspective view of the wall panel showing a portion of Figure 1.1.

The lightened portion of the wall panel surrounded by broken lines forms no part of the claimed design.

1 Claim, 3 Drawing Sheets
